UNITED STATES PATENT OFFICE

JENNIE M. O'CONNOR, OF CHICAGO, ILLINOIS, AND INEZ G. WIER, OF PITTSBURGH, PENNSYLVANIA.

SANITARY PROTECTING-SKIRT.

1,037,514.

Specification of Letters Patent. Patented Sept. 3, 1912.

Application filed September 27, 1911. Serial No. 651,645.

To all whom it may concern:

Be it known that we, JENNIE M. O'CONNOR, a citizen of the United States, residing at 2329 South Lawndale avenue, in the city of Chicago, county of Cook, and State of Illinois, and INEZ G. WIER, a citizen of the United States, residing at 744 Loretta street, in the city of Pittsburgh, county of Allegheny, and State of Pennsylvania, have invented new and useful Improvements in Sanitary Protecting-Skirts, of which the following is a specification.

This invention relates to, and is an improvement in that class of undergarments for women which are designed to protect the outer clothing during the catamenial period.

The object of this invention is to provide a sanitary protecting skirt, which shall be simple in construction and design, can be manufactured more cheaply than any article now manufactured or sold for the same purpose, and can be readily changed or renewed by attaching new or clean aprons thereto, without removal of the skirt from the wearer. This object is accomplished by means of the new article of manufacture, hereinafter described and claimed, reference being had to the accompanying drawings, which are hereby referred to, and which form a part of these specifications.

The said new article of manufacture consists of an ordinary underskirt of permeable material, with an opening in the rear or back portion, to which is attached an apron of impermeable material, which apron can be removed, and another similar apron substituted therefor, without requiring the skirt to be removed from the wearer.

Figure 1 is a view of the underskirt without the apron. Fig. 2 shows the apron or

impermeable portion of the underskirt. Fig. 3 is a view of the sanitary protecting skirt complete, with apron attached, and in place.

In Fig. 1, A, is an ordinary skirt, with yoke D, and facing B, at the top, and having an open space as shown by the lines E, E', E''. The yoke, D, and facing, B, are open or divided at C. The open space enclosed by the lines E, E', E'', is for the reception of the impermeable apron or removable section shown as Fig. 2, and said underskirt is provided with ball and socket or other suitable fastenings, shown as G, G, G, G, by which the apron or removable section shown as Fig. 2, is secured or fastened thereto.

Fig. 2, which is the apron or removable section is constructed of a substantially rhomboidal piece of impermeable material, preferably sheet rubber, or rubber cloth, and is provided with ball and socket or other suitable fastenings, by means of which it is attached to the underskirt at the points shown in Fig. 1 as G, G, G, G, G.

Fig. 3 shows the improved sanitary skirt complete and entire, ready for use, the removable apron or section thereof is indicated thereon as F.

We therefore claim as our invention the following:

An improved sanitary protecting skirt composed of two pieces only, one of said pieces being substantially rhomboidal as described, and adapted to be removed without the removal of the skirt from the wearer.

JENNIE M. O'CONNOR.

INEZ G. WIER.
